UNITED STATES PATENT OFFICE.

ISAAC A. SCHWARZ, OF PHILADELPHIA, PENNSYLVANIA, ASSIGNOR TO HIMSELF AND AUGUSTUS A. LAZARUS, OF SAME PLACE.

DESIGN FOR TRIMMING.

SPECIFICATION forming part of Design No. 27,448, dated July 27, 1897.

Application filed June 19, 1897. Serial No. 641,520. Term of patent 3 $\frac{1}{2}$ years.

To all whom it may concern:

Be it known that I, ISAAC A. SCHWARZ, a citizen of the United States, residing in Philadelphia, Pennsylvania, have invented a certain new and original Design for Trimming, of which the following is a specification.

My design for trimming is fully shown in the accompanying drawings, in which—

Figure 1 is a face view of a piece of the trimming, and Fig. 2 is a rear view of the same.

The design comprises a longitudinal strip *a*, having a chenille face, long chenille loops *b* depending from this strip, and shorter chenille loops *d* being formed above it, the back of said longitudinal chenille strip being plain, as shown at *f* in Fig. 2. Alternating with and crossing the chenille loops *d* above the strip *a* are ribbon loops *g*, and at the top of each of the long depending chenille loops *b*

and in front of the chenille face of the strip *a* are double ribbon loops *h*. Passing through the lower portions of the chenille loops *b* is a cord *i*.

The essential feature of novelty of the design is the combination of the chenille strip and loops with the ribbon loops, said strip and loops being formed and disposed in the manner set forth.

I claim—

The design for trimming, substantially as described and as shown in the accompanying drawings.

In testimony whereof I have signed my name to this specification in the presence of two subscribing witnesses.

ISAAC A. SCHWARZ.
